UNITED STATES PATENT OFFICE.

ROSE O'NEILL WILSON, OF DAY, MISSOURI.

DESIGN FOR A DOLL.

43,680.

Specification for Design.

Patented Mar. 4, 1913

Application filed December 17, 1912. Serial No. 737,311. Term of patent 14 years.

To all whom it may concern:

Be it known that I, Rose O'NEILL WILSON, a citizen of the United States, residing at Day P. O., in the county of Taney and State of Missouri, have invented a new, original, and ornamental Design for Dolls, of which the following is a specification, reference being had to the accompanying drawing, forming part thereof.

Figure 1 is a front elevation of a doll

showing my new design; and Fig. 2 is rear elevation of a doll showing my new design.

I claim:

The ornamental design for a doll as shown
ROSE O'NEILL WILSON
